MACHINE FOR PACKETING CIGARETTES
AND THE LIKEGeorge Daniel Horgan, London, England, assign-
or to American Machine & Foundry Company,
New York, N. Y., a corporation of New JerseyApplication July 29, 1937, Serial No. 156,345
In Great Britain August 1, 1936

4 Claims. (Cl. 226—5)

This invention relates to machines for packeting cigarettes and the like in which the articles are enclosed with cartons of the slide and shell type.

5 An object of the invention is to provide an improved packeting machine which may be arranged as a "single feed" machine and may be readily converted into a "duplex feed" machine without the necessity of altering the driving 10 mechanism, or, if desired, a machine capable of dealing simultaneously with two different size packets.

To this end the invention consists in a packeting machine comprising a turret ring adapted 15 to be rotated about a vertical axis and driven from a main central shaft, a plurality of radiating countershafts adapted to drive units each comprising a slide feed, a folder bed, as at F and at FF, and a shell feed, which units radiate from the turret ring at spaced points, the drive to 20 these units being so arranged that the units may be duplicated and driven directly therefrom.

The invention also comprises a machine for 25 packeting cigarettes or like shaped articles in slide and shell cartons comprising a turret rotating about a vertical axis and driven from a central shaft, a plurality of radiating countershafts adapted to drive each a slide feed unit, a 30 filler unit and a shell feed unit, which units are disposed laterally of the respective shafts, the drive to the units being such that duplex units may be located on the opposite side of the shafts and driven therefrom without alteration of the 35 driving arrangements.

The accompanying diagrammatic drawings illustrate in Fig. 1 in plan a packing machine according to the invention;

Figure 2 is a plan view of the drive for the filler 40 units on a larger scale, and Figure 3 is a plan view of the central part of the turret ring of Figure 1, on a larger scale.

In carrying the invention into effect according 45 to one convenient mode, as applied to the packeting of cigarettes, a turret or ring 1 is provided adapted to be intermittently rotated about a vertical axis from a centrally arranged drive shaft 2. Preferably the drive is effected through gears 3, 4, 5 to a Geneva drive as described in application for United States Letters Patent, Serial No. 111,421, filed November 18, 1936, in the name of John Crighton, and comprising a rotary driving pin 6 adapted to engage radial grooves 7 beneath the turret ring, means (not shown) being

provided for locking the ring intermittently against rotation.

On its upper surface and adjacent its periphery the ring 1 is provided with radial grooves 8 adapted for locating means 9 for receiving the slides 10 of the cartons from a slide feed 11 arranged radially of the ring. The slides are conveyed by the ring to a circumferentially displaced station at which foiled packets of cigarettes are inserted in the slides from a radially arranged hopper and foil feed unit 12 (hereinafter referred to as "filler unit"). The turret ring 1 then conveys the slides with the inserted foiled bundles to a third station where they are removed from the turret and inserted into the shells by a radially arranged shell feed unit 13.

The main units 11, 12 and 13 at the three stations are driven by radially arranged countershafts 14, 15 and 16, which are driven from a bevel gear 17 on the main shaft 2 with which bevel pinions 18, 19, 20 on the countershafts are in mesh.

The countershafts may be arranged at 120° or other suitable angle to each other.

The countershafts 14 and 16 for the slide feed 25 unit 11 and shell feed unit 13 are provided with bevel pinions 21, 22 meshing with pinions 23, 24 associated with the drive shafts of the main slide and shell feed units, which shafts are arranged transversely of the units. The drive from the 30 bevel pinions 23 and 24 to the shafts of their respective units is through a train of gears 27, 28. These main slide and shell feed units 11 and 13 lie to one side of the radial countershafts 14 and 16. The supplementary or duplex slide and shell 35 feed units 25 and 26 are adapted to be driven directly from the bevel pinions 21 and 22 on the outer end of the countershafts 14 and 16 through pinions 34, 35 but as they are mounted on the opposite side of the countershafts to the main 40 units 11 and 13 and the drive to the units is arranged on the opposite hand, the interposition of gear trains becomes unnecessary.

The countershaft 15 for the main and duplex 45 filler units drives the shaft 37 of the main filler unit through a skew gear 38, 39. The shaft 37 of the main unit is arranged longitudinally thereof and at the side. Adjacent the skew gear 38, 39 the shaft 37 is provided with a bevel pinion 30 by which the duplex filler unit 31 is adapted to be 50 driven, the shaft 32 of the duplex unit being provided with a meshing bevel pinion 33.

It will be appreciated that the shaft 32 of the duplex filler bed unit is on the side of the duplex unit adjacent to that of the main filler bed unit. 55

With the improved arrangement of layout and driving means, the supplemental or duplex units 25, 26, 31 may thus be readily applied to the machine, requiring only bolting in place so that 5 the appropriate gears 21, 34; 22, 35; 30, 33 are in mesh. The beds of the units are provided with supporting brackets which are bolted to the mounting 40 of the machine.

The disposition of the main units 11, 12, 13 is 10 such that alternate slide engaging elements on the ring are used, the remainder of the elements being for the supplementary or duplex units 25, 26, 31. By this arrangement the machine may be operated in connection with a single supply of 15 cigarettes using only the main units, or by the addition of the supplementary or duplex units the machine may be converted into a duplex machine thus doubling the output, or two different brands of cigarettes may be packed simultaneously, or by the substitution of the appropriate parts, 20 the machine may deal with two different size packings at the same time.

The particular construction of the various elements of the units forms no part of the invention 25 and will therefore not be dealt with herein.

I claim:

1. A machine for packeting cigarettes or like-shaped articles, comprising a turret ring rotatable about a vertical axis, a central drive shaft, 30 means for driving the turret from said shaft with an intermittent motion, a plurality of radiating countershafts driven from the central shaft, and a plurality of packing units driven from the countershafts, said packing units being disposed 35 in pairs of duplex packing units, and means to connect each unit of each pair to one of said countershafts, one unit of each pair being intergeared with its particular countershaft permanently and the other unit of each pair having 40 a readily disconnectible driving gear set connecting said countershaft and unit.

2. A machine for packeting cigarettes or like shaped articles; said machine comprising a turret ring, means for driving the ring with an intermittent motion about a vertical axis, a plu- 45

rality of driving means located adjacent to the periphery at spaced portions of the ring, a plurality of packing units driven by said driving means, said packing units being disposed in pairs of duplex packing units, and means to connect each unit of each pair to an appropriate part of said driving means adjacent to the periphery at a suitable point, at least one unit of each of said pairs being readily removable to convert said turret from a twin feed operation to a single feed 10 operation. 5

3. A machine for packeting cigarettes or like-shaped articles comprising a turret ring, means for intermittently rotating the turret about a vertical axis, a plurality of radiating counter- 15 shafts driving packing units co-operating with the turret, said packing units being disposed in pairs of duplex packing units, one pair in juxtaposition with each countershaft, and connections whereby each countershaft drives each unit of 20 its pair, one unit on either side of the shaft.

4. A machine for packeting cigarettes or like shaped articles in slide and shell cartons, comprising a turret ring, means for intermittently rotating the turret about the axis of a vertical 25 shaft, said turret having means adapted to hold the slides, a plurality of radiating countershafts arranged in spaced relation around the turret, one of said countershafts being adapted to drive one or more slide feed units; a second radiating 30 countershaft adapted to drive one or more shell feed units, a third radiating countershaft adapted to drive main and duplex filler units; said radiating countershafts and units being arranged in spaced relation around the turret, with bevel 35 gearing by which said radiating countershafts are driven from said main shaft; a main filler unit provided with a fourth countershaft and skew gearing intermediate said last-named countershaft and said third radiating countershaft; 40 and a duplex filler unit provided with a fifth countershaft and bevel gearing by which said fifth countershaft and the duplex filler unit are driven from the fourth countershaft. 45
